UNITED STATES PATENT OFFICE.

DIXON L. BEAN, OF CHICAGO, ILLINOIS, ASSIGNOR TO HAMILTON-ROSS FACTORIES INCORPORATED, OF CHICAGO, ILLINOIS, A CORPORATION OF ILLINOIS.

DESIGN FOR A LAMP BASE.

Application filed November 2, 1928. Serial No. 28,740. Term of patent 7 years.

To all whom it may concern:

Be it known that I, DIXON L. BEAN, a citizen of United States, residing at Chicago, in the county of Cook and State of Illinois, have invented a new, original, and ornamental Design for Lamp Bases, of which the following is a specification, reference being had to the accompanying drawing, forming part thereof, in which,—

The Figure 1 is a top plan view of a lamp base showing my new design, and Figure 2 is a side elevation.

I claim:

The ornamental design for a lamp base, as shown.

In witness whereof I affix my signature.

DIXON L. BEAN.
